UNITED STATES PATENT OFFICE.

HENRY L. HATHAWAY, OF CINCINNATI, OHIO.

BELT-FASTENER.

1,259,735.

Specification of Letters Patent. Patented Mar. 19, 1918.

Application filed June 29, 1916. Serial No. 106,599.

To all whom it may concern:

Be it known that I, HENRY L. HATHAWAY, a citizen of the United States, residing at Cincinnati, in the county of Hamilton and 5 State of Ohio, have invented certain new and useful Improvements in Belt-Fasteners, of which the following is a specification.

My invention relates to belt fasteners, and is especially applicable for fastening the 10 ends of woven belting, such as cotton belting and rubber belting, the latter, in practice, having a woven body. The character of belting to which my invention applies is belting employed for power purposes, for 15 instance, for being received about pulleys for driving machinery, or for conveying material.

It is the object of my invention to provide a fastener having piercing prongs so 20 constructed, positioned and arranged as to pierce the fabric and to force the strands of the fabric out of their normal planes into deflected lines about and between the piercing prongs, the piercing prongs being 25 arranged in offset relation and comprising longer piercing prongs arranged to be laid over toward shorter piercing prongs for crowding the deflected strands between the said prongs. The shorter prongs may, if 30 desired, be clenched upon the ends of said longer prongs.

The invention will be further readily understood from the following description and claims, and from the drawing, in which lat- 35 ter—

Figure 1 represents a plan view of two proximate ends of a textile belting, partly broken away.

Fig. 2 is a longitudinal section of the 40 same taken on the line 2—2 of Fig. 1.

Fig. 3 is a bottom view of the belt fastener.

Fig. 4 is a side elevation of the same.

Fig. 5 is a bottom face view of the proximate ends of the belting, showing the prong side of the fasteners, the belt being partly broken away; and

Fig. 6 is a diagonal section of the same taken on the line 6—6 of Fig. 5.

11, 12, represent the proximate ends of a belt 13, the ends of which are arranged to abut one another, as shown at 14. The belting exemplified is a woven belting, for instance a cotton belting, although it is to be 55 understood that my invention is also appli-

cable to other characters of woven beltings, for instance, rubber belting.

The belt fasteners are exemplified at 15, and comprise piercing prongs 16 which are diagonally arranged at the respective corners of the plate 17 of the fastener, as exemplified in Fig. 3. The fastener also comprises piercing prongs 18 which are exemplified as being shorter than the piercing prongs 16 and are preferably arranged at 60 the intersection of planes perpendicular to the width of the piercing prongs 16. One of the piercing prongs 18 is located in offset relation between each pair of piercing prongs 16 for forming slanting spaces 19 65 between the piercing prongs 18 and the piercing prongs 16. The piercing prongs taper toward their upper ends and their upper ends terminate in points for readily piercing the fabric and deflecting the 70 strands thereof without shredding or cutting the latter.

There is one of the pair of piercing prongs 16 and their coacting piercing prong 18 located at each end of the fastener. 80

In employing my improved fastener, the piercing prongs at the respective ends of the same are forced through the web of the woven belting.

Woven belting to which my invention 85 is particularly applicable comprises warp strands 21 forming the warp of the belting and weft strands 22 forming the woof of the belting. When piercing the belting, the arrangement of the piercing prongs causes 90 the strands of the woven belting to shift for arranging the warp strands received in the spaces 19 in slanting manner in said spaces, as shown at 23, the weft strands being also arranged in slanting manner in said spaces, 95 as shown at 24.

The piercing of the woven belting by the piercing prongs causes the warp and weft strands to arrange themselves out of their normal lines in the spaces between said 100 prongs and to be compressed in said spaces by the piercing action.

After the prongs have pierced the belting, the ends of the longer prongs 16, which extend through the belting, are bent diagonally with relation to each other and the plate toward the coacting prong 18, as shown at 25, this action further compressing the strands, and insuring a firm grip 105 upon the warp and weft strands between 110

- each prong 16 and the prong 18 for definitely holding said strands in place and preventing shifting of the same in said spaces, the security of the fastening being further enhanced by the fact that the rearrangement of the strands is local only at the prongs, the weaving being maintained in normal condition between said prongs and the ends of the belting, as indicated at 26.
- 10 If desired, the outer ends of the piercing prongs 18 may be spread, as shown at 27, upon the proximate ends of the piercing prongs 16 after the latter have been bent toward the piercing prong 18 for holding the ends of the piercing prongs 16 securely toward the woven belting and locking the same rivetwise in place.
- 15 The widths of the piercing prongs 19 preferably extend in the direction of the length of the plate and belting.
- 20 My invention provides a very simple belt fastening for woven belting, easily applied, and so arranged as to provide extremely firm securing connection.
- 25 Having thus fully described my invention, what I claim as new and desire to secure by Letters Patent, is:
- 30 1. A belt fastener, comprising a substantially rectangular plate, piercing prongs extending perpendicular to said plate at the respective corners thereof, the widths of said piercing prongs arranged diagonally of said corners, and a piercing prong adjacent to each end of said plate extending perpendicular to said plate and located at the point of intersection of the planes perpendicular to the widths of said first-named piercing prongs at the end of said plate adjacent to which said last-named piercing prong is located, for forming spaces between
- 35
- 40

45 said first-named piercing prongs and said second-named piercing prongs extending slantingly across the ends of said plate, the ends of said first-named piercing prongs at each end of said plate extending through the belting and arranged to be bent toward the adjacent one said second-named piercing prongs, and said last-named prong spread upon said adjacent ones of said first-named piercing prongs.

50 2. In a belt fastener, the combination with the proximate ends of belting, of an integral substantially rectangular plate lapping both said ends at one side thereof, each corner of said plate having a long prong extending substantially perpendicular from said plate through said belting ends, and each end portion of said plate having an additional prong extending substantially perpendicular from said plate and spaced from the outer end of said end portion on which the same is located, said additional prong located substantially equidistant from said long prongs at said last-named end, the outer ends of said long prongs bent diagonally crosswise of the other side of said ends of belting into proximity with the adjacent additional prong, which additional prong extends through said belting and past said last-named outer ends of said long prongs, and the outer end of said short prong spread by upsetting upon said outer ends of said adjacent long prongs.

55 60 65 70 75 In testimony whereof, I have hereunto signed my name in the presence of two subscribing witnesses.

HENRY L. HATHAWAY.
